VENETIAN BLIND MECHANISM

Harry G. Balthasar, West Tower Park, Ohio, assignor to The Edward J. Hoff Company, Cincinnati, Ohio, a corporation of Ohio

Application May 6, 1938, Serial No. 206,439

14 Claims. (Cl. 156—17)

This invention relates to the mounting brackets for supporting the head rail of the Venetian blind within the window frame. More specifically, the present invention is directed to improvements in the mounting brackets for removably securing the head rail of the Venetian blind to the window frame.

As now in common use, Venetian blinds comprise a plurality of slats suspended from a main 10 tilting bar and arranged to be tilted open or closed by movement of the bar. The tilting bar is pivotally mounted, preferably upon the lower side of a head rail which is secured to the window frame. The mechanism for lowering and 15 raising the slats of the blind also is mounted on the head rail. Both the tilting and the elevating and lowering apparatus of the blind are controlled by means of pull cords depending from the head rail of the blind. Since the entire blind 20 assembly is hung from the head rail, which in turn is supported by the brackets secured to the window frame, by simply disengaging the head rail from the supporting brackets of the window frame, the blind may be bodily dismounted.

25 The tendency of the slats to collect dirt and dust which, of course, renders the blinds unsightly and necessitates frequent cleaning, is one of the faults of Venetian blinds. They are quite difficult to clean especially when in place in the 30 window frame. Therefore, it has been found expedient to provide a convenient means for dismounting the entire blind assembly from the window frame whenever the blinds are to be cleaned, or at such times when it occasionally 35 becomes necessary to dismount them for adjustment or repairs.

The improved supporting brackets of the present invention permit ready removal of the blind from the window frame without disturbing the 40 adjustment of the blind relative to the window frame. The brackets are very simple to operate and designed to permit even the least mechanically minded person to take the blind down for cleaning or repairs, and to replace the blind after 45 this is done. The importance of this feature to housewives is evident.

The brackets for mounting the head rail must necessarily provide a rugged anchorage for the 50 rail because, in addition to the weight of the blind assembly, the strain of the pull cords in adjusting the blind, is imposed on the head rail. The brackets are designed to withstand lateral as well as perpendicular stress for the reason that the 55 pull cords are often manipulated at an angle to

the window, thus tending to pull the blind assembly inwardly.

It has been the primary objective of the present inventor to provide brackets for the head rail of a Venetian blind assembly that permit 5 the convenient dismounting of the blind by a housewife, or other mechanically unskilled persons, when the blind is to be cleaned or the worn parts renewed, and also permit replacement of the blind after the cleaning or repairs have been 10 completed.

It has been another objective of the present inventor to provide a mounting bracket including a latching device which is self-acting with respect to the head rail and thereby automatically latches the rail in place on the supporting bracket when it is adjusted to supporting relationship with the bracket. Thus the person mounting the blind has the use of both hands 15 in manipulating the blind assembly.

It has been still another objective to provide a bracket in which the weight of the blind assembly is sustained upon a rigid flange member and in which a locking means is provided to hold the rail against accidental lateral displacement 20 relative to the supporting flange.

Briefly, it is the concept of the present invention to support the head rail and Venetian blind assembly removably upon brackets having rigid supporting flanges and to provide automatically 30 actuated locking devices to lock the rail against lateral displacement relative to the flanges.

Further objectives of the invention will be more fully apparent from the description of the accompanying drawings illustrating a preferred 35 embodiment of the invention in which:

Figure 1 is a general view of a window having a Venetian blind supported therein by means of the present brackets.

Figure 2 is a fragmentary front view partially 40 in section of one of the brackets showing the head rail in place therein.

Figure 3 is a sectional view taken on line 3—3, Figure 2 showing the head rail partially inserted into the bracket with the latching element displaced by the inner edge of the head rail.

Figure 4 is a sectional view similar to Figure 3 showing the head rail completely inserted within the bracket and the latch in locking position. 50

Figure 5 is a sectional view taken on line 5—5, Figure 2.

Figure 6 is a fragmentary perspective view illustrating one of the mounting brackets in place in the window frame and the head rail in po- 55

sition within the bracket with the remainder of the blind assembly omitted for simplifying the view.

Figure 7 is a sectional view taken on line 7—7, Figure 5.

Figure 8 is a front view illustrating a head rail mounting bracket of modified design.

Figure 9 is a sectional view taken on line 9—9 of Figure 8.

Figure 10 is a sectional view similar to Figure 9 showing the action of the latching element of the bracket as the head rail is inserted therein.

Figure 11 is a view similar to Figure 8, illustrating a further modification of the bracket.

Figure 12 is a sectional view of the bracket illustrated in Figure 11.

Figure 13 is a view taken similar to Figure 11 showing the latching device in position for permitting removal of the head rail from the bracket.

Figure 14 is a sectional view taken on line 14—14 of Figure 12.

Figure 15 is a sectional view taken on line 15—15, Figure 14.

Referring to Figure 1 of the drawings, a Venetian blind 15 is illustrated in position within a window frame 16. The blind assembly is hung from the head rail 17, which in turn, is supported within the window frame by means of the mounting brackets 18.

The Venetian blind includes the usual tilting bar 19 from which is suspended the ladder tapes 20 for supporting the blind slats 21. The blind is raised and lowered by means of the pull cord 22 and the angle of the slats is adjusted by means of the tilt cord 23. The mechanism for actuating the blind is secured to the underside of the head rail, but since this mechanism forms no part of the present invention, a detailed disclosure of the same has been omitted.

Referring to Figures 2 to 7 inclusive, illustrating one form of the invention, the body portion of the bracket comprises a rectangular sheet metal plate having a flange 24 extended at right angles from its upper edge and an angular flange 25 extending at right angles from the inner side edge thereof. The main panel and the flanges of the bracket are provided with a plurality of apertures for the screws 26 securing the bracket to the window frame. This bracket, therefore, provides three attaching faces, any or all of which may be employed, depending upon the window arrangement, that is, the availability of surfaces to which the attachment may be made.

The body of the bracket further carries an angle piece providing an angular flange 27 adjacent the upper flange 24. The angle piece is secured to the body of the bracket preferably by means of spot welding and is positioned to dispose the upper web of the angle piece in a horizontal plane parallel to the flange 24. The flange 27 is spaced downwardly a short distance from the upper flange 24 to permit the insertion of the head rail 17 therebetween with the weight of the head rail imposed upon the flange 27.

In the present instance, the head rail 17 is of channel configuration and is provided with adjustable end extensions 28 for permitting the length of the head rail to be varied to suit the width of the particular window to which it is fitted. The end extensions 28 are secured to the head rail by means of screws and wing nuts

29. The screws are disposed in longitudinal slots 30 for permitting the longitudinal adjustment of the end section 28 relative to the head rail. By means of this construction, the head rail may be fitted to the particular window frame 5 and will accommodate variations in the width of the frame. After having been properly adjusted and set, the wing nuts are tightened to clamp the extensions in position and no further attention is needed. The adjustable feature may be omitted if desired and the ends of the head rail directly supported in the brackets.

In applying the blind to the window frame after the brackets have been installed, the ends of the head rail are inserted into the throat or 15 channel provided between the angular flange 27 and the top flange 24 and slide laterally inwardly of the bracket. The forward edge of the flange 27 is curved downwardly as at 27a to facilitate insertion of the head rail into the 20 bracket.

The bracket includes a vertically slidable latching member 31 which cooperates with a slot 32 in the end extension of the head rail to lock the same in place. The latching element 31 at 25 its upper end is bent to form a U-shaped latching head providing a latching lug or dog 33. The lower edge of the lug is inclined to form a cam surface as at 34, adapted to be engaged by the inner edge of the head rail and to raise 30 the latching member as the head rail is moved inwardly of the bracket.

The latching member is slidably engaged in the bracket in a slideway 35 in the attaching web of the angle piece and at its upper end 35 is disposed through an opening 36 in the top flange 24 of the bracket. The shank 37 of the latching element includes adjacent shoulders 38 adapted to engage the abutments 39 formed in the slideway 35. The engagement of the shoulders limits the upward movement of the latching element and prevents removal of the same. The lower end of the latching element is provided with an angular extension 40 which provides a finger hold for raising the latching 45 element manually when it is desired to disengage the head rail from the bracket. The shoulders or abutments 39 are formed by pressing a portion 31a of the attaching web of the angle piece outwardly into a plane beyond the latch 50 31. Thus a guideway is constituted preventing outward displacement of the latch. It will be noted in Figure 2 that the angular flange at the top of the bracket is provided with an offset portion 41 to space the bracket downwardly 55 from the upper member of the window frame. This offset portion provides clearance for the upper end of the latching member so that the head of the latching member is free to move a sufficient distance upwardly to disengage from the slot 32 of the head rail.

It will be observed that the action of the latch element is automatic when the head rail is inserted within the bracket. This action is provided by the inclined cam face 34 of the 65 clamping head. As the head rail passes beneath the cam surface, the clamping element remains elevated until the slot 32 of the head rail is in alignment with the clamping head at which time the latching head drops by gravity into the 70 slot to latch the head rail in place.

When it is desired to remove the head rail, the clamping elements of each bracket are disengaged by manually raising the elements to their upward positions and holding them there 75

while withdrawing the head rail from the brackets by sliding the same laterally. After the rail has been completely removed, the latching elements drop by gravity into position to latch the head rail automatically again when it is replaced.

Referring to Figures 8 to 10 inclusive, a modified type of bracket is illustrated in which the action is substantially the same as above described. In this form, however, the latching element is in the form of a spring indicated at 42. The body of the bracket is formed in the same manner as the form just described and includes the angular supporting flange 27 as previously described. The rear upwardly turned end of the latching spring is anchored in an aperture 43 in the supporting flange 27 and the shank of the spring is clamped by means of the clip 44. The forward end of the spring is bent to provide an inclined cam surface 45 and a latching abutment 46. The outer end of the spring further includes a ring 47 to facilitate finger engagement for drawing the spring downward to release the head rail as in the previously described form. The bracket is provided with a projecting stop element 48 which limits the downward movement of the latch spring 42 so that permanent deformation of the spring by undue downward movement is prevented.

In the present example, the head rail is clamped along its outer edge rather than by means of a slot, the outer edge of the head rail being engaged by the spring abutment 46 which extends upwardly from the angular flange 27 and projects into a notch 49 formed in the upper angular flange 24. The weight of the head rail and blind assembly is supported upon the angular flange member 27 in the same manner as in the previous form.

Figures 11 to 15 inclusive illustrate another modification of the bracket. The bracket elements are similar to those of the previously described forms, the weight of the head rail being sustained on the angular flange 27. In this form, however, the latching element is secured on the head rail rather than on the bracket. The latching element consists of a pivoted locking finger 50 adapted to engage in a notch 51 of the bracket 27. The pivoted end of the finger is engaged around a pin 52 disposed within a slot 53 of the rail. In the position shown in Figure 12, the locking finger is engaged within the notch 51 and thus holds the rail against lateral displacement.

In this form of the invention, the brackets latch automatically in the same manner as in the other two forms. In order to provide this automatic action, the inner edge of the support flange 27 is formed to provide an inclined cam surface as at 54 (see Figure 15). Upon insertion of the head rail within the throat of the bracket the latching finger is swung inwardly by contact with the cam surface and drops inwardly into the notch 51 when the rail is fully inserted within the throat. When it is desired to remove the rail, the locking finger is swung to the position as illustrated in Figure 13 at which time the finger is clear of the notch and the rail may be withdrawn from the bracket.

Having described my invention, I claim:

1. A Venetian blind supporting mechanism, comprising, a head rail consisting of an inverted channel-shaped element having its base wall extended to provide supporting portions, brackets for securing the respective ends of the head rail in position in a window frame, each of said

brackets providing a horizontal flange and a vertical side, a supporting flange fixed in each bracket providing a supporting surface spaced from and parallel to the horizontal flange, said supporting flange and horizontal flange providing a throat into which the respective supporting portions of the head rail may be inserted, and means for locking the head rail in position in the brackets. 5

2. A mounting bracket for securing the head rail of a Venetian blind within a window frame, comprising a body element, to be secured to said window frame, a supporting member secured to said body element and adapted to support said head rail, a latching element mounted on said bracket and slidable vertically relative to said bracket, and an inclined cam member on said latching element adapted to be moved vertically by engagement with the head rail upon insertion of said head rail adapting said latching element to engage the rail to latch the same in place on said supporting member. 10 15

3. A supporting bracket for Venetian blind head rail comprising an element having a vertical flange and a horizontal flange extending from said vertical wall, a supporting flange fixed in said element and disposed parallel with respect to the horizontal flange in spaced relationship thereto whereby the Venetian blind may be inserted between said supporting flange and the horizontal flange and a spring urged latch mounted on the bracket and including a cam surface disposed into the space between the parallel flanges engageable by the head rail when it is moved into the space, said latch automatically effective for returning to normal position when the head rail is in position. 25 30 35

4. For use in a Venetian blind having a head rail consisting of an inverted channel-shaped element having its base wall extended to provide supporting portions, a bracket for securing the end of the head rail in position in a window frame, said brackets providing three flanges, namely, an upper horizontal flange, a vertical side flange, and a vertical rear flange, a supporting flange fixed in each bracket providing a fixed supporting surface spaced from and parallel to the horizontal upper flange, said supporting flange and upper horizontal flange providing a throat into which the respective supporting portions of the head rail may be inserted. 40 45 50

5. A Venetian blind supporting mechanism, comprising, a head rail consisting of a channel-shaped element having relatively flat ends, brackets for securing the respective ends of the head rail in position in a window frame, each of said brackets providing three flanges, namely, an upper horizontal flange, a vertical side flange, and a vertical rear flange, a supporting flange fixed in each bracket providing a supporting surface spaced from and parallel to the horizontal upper flange, said supporting flange and upper horizontal flange providing a throat into which the respective flat end of the head rail may be inserted and, an automatic latching device in each bracket for locking the head rail in position in the bracket, said device effective merely by insertion of the head rail. 55 60 65

6. A supporting bracket for Venetian blind head rail, comprising, an element having a pair of vertical walls at right angles to each other and a horizontal wall extending from said vertical walls, a supporting flange fixed in said element and disposed parallel with respect to the horizontal wall in spaced relationship thereto where- 70 75

- 5 by the end of the head rail of the Venetian blind may be inserted between said supporting flange and the horizontal wall, a latch mounted for vertical movement in the bracket including a cam surface for moving the latch vertically when the head rail is moved into the throat and automatically effective for returning to normal locking position when the head rail is in position.
- 10 7. In a Venetian blind, a head rail, supporting brackets for said rail, each bracket comprising, a plate adapted to be fixed in position in a window frame and providing horizontally disposed spaced flanges immovable with respect to each other and constituting a throat for receiving the 15 end of the head rail, and latches pivotally carried by the head rail, one at each end thereof, each bracket providing a slot for receiving the adjacent latch, said bracket including a cam surface leading up to the slot for automatically lifting the latch when the head rail is inserted.
- 20 8. A supporting bracket for a Venetian blind head rail, comprising, a plate adapted to be fixed in position in a window frame and providing horizontally disposed spaced flanges immovable with 25 respect to each other and constituting a throat for receiving the head rail, and a latch carried by the bracket, said bracket providing a vertical guideway for said latch, said latch including a downwardly projected flange having an inclined 30 lower surface engageable by the head rail for raising the latch and permitting insertion of the head rail, said latch free to drop by gravity into latching position with respect to the head rail.
- 35 9. A supporting bracket for a Venetian blind head rail, comprising, an element having a vertical flange and a horizontal flange extending from said vertical flange, a supporting flange fixed in said element and disposed parallel with respect to the horizontal flange in spaced relationship 40 thereto whereby the Venetian blind may be inserted between said supporting flange and the horizontal flange, a latch mounted for vertical sliding movement in the bracket including a downwardly facing cam surface engageable by 45 the head rail for moving the latch vertically when the head rail is moved into the throat, said latch dropping to normal position when the head rail is in position.
- 50 10. A Venetian blind supporting mechanism, comprising, a head rail having relatively flat ends, brackets for mounting the respective ends of the head rail in position in a window frame, each of said brackets providing horizontal flanges, the flanges of each bracket being spaced apart a sufficient distance to permit insertion of the ends of the head rail and being relatively immovable, and a vertically urged latch for lock- 55 ing the respective ends of the head rail in position in the brackets when inserted therein.
- 5 11. In a Venetian blind having a head rail, said rail provided with openings at opposite ends adapted to cooperate with latching means, support brackets, each bracket including a substantially horizontal channel adapted to receive an end of said rail for supporting the same, a latching device, said latching device operative relative to said channel and adapted to engage the adjacent opening in said rail, an inclined cam surface on said latching device adapted to be engaged by said rail to move said latching device clear of said channel to permit insertion of said rail therein, whereby said latching device engages the opening in said rail upon registration therewith and latches the rail in place in said channel. 10
12. In a Venetian blind having a head rail provided with openings at opposite ends thereof 20 adapted to cooperate with latching means, support brackets, each bracket including a substantially horizontal channel member adapted to receive an end of said head rail for supporting the same, a self-acting latching device, said latching device mounted in operative relationship with said channel member and adapted to engage the adjacent opening in said rail upon insertion of the rail into said channel member and manually operated means for releasing said 30 latching device for demounting said rail.
13. In a Venetian blind, a head rail, said rail having latching fingers at opposite ends thereof adapted to cooperate with mounting brackets, brackets for demountably supporting said rail, each bracket having a horizontal shelf adapted to support an end of said head rail, said shelf provided with a latching notch, said latching fingers adapted to cooperate with said notches, whereby upon insertion of the end of said rail 40 into said channel, said latching fingers may be actuated to engage said notches and lock the rail against lateral displacement. 45
14. A mounting bracket for securing the head rail of a Venetian blind comprising, a body element including a head rail supporting member and a latching spring, said spring including a resilient shank member anchored at one end to said bracket and having its opposite end configurated to form an inclined cam surface and a latching abutment adapted to engage said rail, whereby upon contact of said cam surface with said rail, said cam surface and latching abutment are actuated out of the path of said rail and subsequently move into engagement with said rail to latch the same in position relative to said supporting member. 55

HARRY G. BALTHASAR.
